SHOCK RESISTING LAMP RECEPTACLE

Robert A. Blood, Syracuse, N. Y., assignor to
Crouse-Hinds Company, Syracuse, N. Y., a cor-
poration of New York

Application March 31, 1939, Serial No. 265,321

2 Claims. (Cl. 173—358)

This invention relates to shock resisting lamp receptacles and has as a general object an improvement of that type of device as shown in my copending application, Sr. No. 111,269, filed November 17, 1936, which matured into Patent No. 2,174,773, on October 3, 1939.

More particularly the invention has as an object a shock resisting lamp receptacle embodying a structure whereby the screw shell is permitted to move axially relative to the body with the contacts for connecting the device to the supply wires being fixedly secured to the screw shell and its center terminal and serving as spring means to urge the screw shell in one direction and a separate spring means urging the screw shell in opposite direction against the spring tension of the contacts.

The invention consists in the novel features and in the combinations and constructions hereinafter set forth and claimed.

In describing this invention, reference is had to the accompanying drawings in which like characters designate corresponding parts in all the views.

25 Figure 1 is a vertical sectional view of a shock resisting lamp receptacle embodying my invention illustrating the receptacle mounted in a lighting unit.

Figure 2 is a plan view of the open end of the receptacle.

30 Figure 3 is a plan view of the top end of the receptacle.

Figure 4 is a plan view of the open end of the body of the receptacle with the screw shell removed.

35 Figure 5 is a vertical sectional view of the receptacle being on substantially lines 5—5, Figure 2.

Figure 6 is a top plan view of the screw shell member.

40 Figure 7 is a side elevational view of the thrust spring employed in the receptacle.

The receptacle comprises a body member 10 formed or molded from suitable plastic material.

45 The body is preferably provided with an externally threaded portion 11 to permit the receptacle to be screwed into the body 12 of a lighting fixture. The body 10 is formed with a substantial recess, the outer portion of which is enlarged as at 13. The peripheral margin, about the enlargement 13 of the recess, is provided with a plurality of threaded apertures 14 to receive screws 15 employed to secure an annular member 16 to the open end of the body and which extends 50 inwardly and overlaps the enlargement 13 of the

recess. A pair of spring contacts 17, 18 are mounted in the bottom of the recess and are secured to the body at like ends by screws 19 which are here shown as threading into metallic inserts 20, and to the outer end of which are secured terminals 21 provided with binding screws 22 to permit the receptacle to be wired to the supply lines.

The screw shell member consists of a metallic shell 23, a disk 24 of insulating material, and a central terminal 25. The disk 24 is secured to the inner end of the screw shell by rivets 26. The terminal 25 extends from the center of the disk outwardly and is bent over the edge of the disk and extends inwardly across the top of the same, the free end being secured to the disk by a rivet 27. The bight of the terminal is arranged in a slot 28 and both legs of the terminal and the disk are provided with apertures 29. The screw shell 23 is provided with a tab portion 30 extending inwardly across the top of the disk 24 and provided with an aperture 31 arranged in register with a similar aperture in the disk.

The free end of the contact 17 is secured to the central terminal 25 by a screw 34 extending through the terminal and threading into aperture 35 in contact 17. Contact 18 is secured to the tab 30 of the screw shell in a similar manner by screw 36. The contacts 17, 18 are formed of spring material and tend to urge the screw shell member of the receptacle inwardly toward the bottom of the recess.

30 The screw shell 23 is formed with a radially extending flange 38 arranged in the enlargement 13 of the recess, and the screw shell is encircled by a thrust spring 39 having depending portions 40 engaging the flange 38, the annular portion of the spring 39 engaging the bottom of the enlargement 13. The spring 39 acts against the flange 38 to yieldingly urge the screw shell 23 outwardly against the tension of the spring contacts 17, 18. In this manner, the screw shell is provided with a floating mounting and is permitted an axial movement relative to the body 10. Axial movement of the screw shell 23 in both directions is limited by engagement of the flange 38 with the bottom of the enlargement 13 of the recess, or with the annular member 16. The body is provided with an axially extending slot 45 in the wall of the recess, and the screw shell with a projection 46 slidably mounted in the slot 45 and serves to prevent rotation of the screw shell relative to the body.

45 It will be observed that the contacts 17, 18 are fixedly connected to the screw shell and the cen- 50

tral terminal 25. Accordingly, there is a continuous metallic circuit from the feed wires to the screw shell and the central terminal 25 and which does not employ spring pressed connections as is customary in devices of this type.

5 I have found that the spring 39 acting in opposition to the spring contacts 17, 18, renders the receptacle more sensitive to vibrations of small magnitude such as those resulting from the operation 10 of machinery in the building. At the same time, the screw shell is adequately supported and is maintained in normal position relative to the body whereby the lamp bulb does not become moved out of focus with the lighting unit in which 15 the receptacle is mounted.

What I claim is:

1. A shock resisting lamp receptacle comprising a body formed with a recess, a screw shell mounted in said recess and having a central terminal and being provided at its periphery with a radially extending flange, a pair of spring contacts mounted at the bottom of said recess and being secured at like ends to the body and at 20 their opposite ends to said screw shell and central terminal respectively, said spring contacts yielding 25 urged said screw shell inwardly toward the bottom of said recess, spring means encircling

said screw shell and coacting with the body and the flange of the screw shell to yieldingly urge the latter outwardly against the tension of said spring contacts, and said flange coacting with the body to limit axial movement of said screw 5 shell.

2. A shock resisting lamp receptacle comprising a body formed with a recess, said recess being enlarged at the open end thereof, a screw shell arranged in said recess and being provided with a central terminal and a radially extending flange arranged in the enlarged portion of said recess, a pair of spring contacts mounted at the bottom of said recess and being secured at like ends to the body and at their opposite ends to said screw 10 shell and central terminal respectively and being operable to yieldingly urge said screw shell inwardly toward the bottom of said recess, an annular member detachably secured to the open end of the body and overlying the enlarged portion 15 of said recess, a spring encircling said screw shell and arranged intermediate the bottom of the enlarged portion of said recess and the flange of said screw shell and being operable to yieldingly urge said screw shell outwardly against the tension of said spring contacts.

ROBERT A. BLOOD.
